ROTARY MOWER HOUSING

Curtis T. Morris and Thomas E. Coners, Lamar, Mo., assignors, by mesne assignments, to RPM Manufacturing Company, Lamar, Mo., a corporation of Missouri

Application May 28, 1952, Serial No. 19,924

Term of patent 14 years

(Cl. D40—1)

To all whom it may concern:

Be it known that we, Curtis T. Morris and Thomas E. Coners, citizens of the United States of America, residing at Lamar, in the county of Barton and State of Missouri, have invented a new, original and ornamental Design for a Rotary Mower Housing, of which the following is a specification, reference being had to the accompanying drawing, forming part hereof.

In the drawing:

Fig. 1 is a top perspective view of a rotary mower housing showing our new design.

Fig. 2 is a bottom perspective view of the rotary mower housing on a somewhat reduced scale.

Fig. 3 is a top perspective view of the rotary mower housing on a slightly reduced scale as compared with Fig. 1, and showing the housing from its opposite side.

Figs. 4 and 5 are views respectively taken in cross section on the lines 4—4 and 5—5 of Fig. 3.

We claim:

The ornamental design for a rotary mower housing, as shown.

CURTIS T. MORRIS.
THOMAS E. CONERS.
